(57) **CLAIM**

The ornamental design for a flexible container, as shown and described.

DESCRIPTION

FIG. 1 is a perspective view of the flexible container showing our new design;

FIG. 2 is a front elevational view thereof, the rear elevational view being omitted because it is a mirror image of FIG. 2;

FIG. 3 is a right side elevational view thereof;

FIG. 4 is a left side elevational view thereof;

FIG. 5 is a top plan view thereof; and,

FIG. 6 is a bottom plan view thereof.

1 Claim, 2 Drawing Sheets

FIG. 1
